VIBRATING SCREEN

Peter H. Toepfer, Milwaukee, Wis.

Application December 15, 1933, Serial No. 702,490

1 Claim. (Cl. 209—326)

This invention pertains to vibrating screens, and more particularly to screens of the positive actuated type, in which vibratory movement is imparted to the frame of the screening medium by means of an eccentric connection between the screen frame and a power-driven shaft journaled in stationary bearings.

The invention has primarily for its object to improve screens of the foregoing type, and in order that a full appreciation of the invention may be had, the objections encountered in conventional screens now in use will be briefly discussed.

Resiliently supported screens, which receive their vibratory action from over-balanced weights or pulleys, have a number of inherent objections, primary of which is that a resultant vertical, elliptical, vibratory action is imparted to the screen, instead of a circular movement. Consequently, the material has a tendency to flow or slide, rather than roll, as it travels down the screen, thus preventing the top material from contacting with the screen. Naturally, the elliptical path of movement of the screen becomes elongated as the screen is loaded. Also, the live load exerted upon the resilient supports transmits a secondary vibration to the screen frame, which is objectionable, and necessitates an extremely heavy structure to overcome the same.

In an endeavor to remedy the foregoing objections, the conventional end support, positive actuated type of screen was developed, wherein the weight of the screen is intended to be supported entirely by the resilient end supports, and positive circular, vibratory movement is imparted to the screen by eccentrics. While screens of this structure overcome certain objections, in screens actuated by over-balanced weights other serious problems and objections are encountered, in that the eccentric shafts must be accurately counter-balanced, necessitating an adjustable counter-balance, which requires a lengthy and tedious, if not impossible, operation by the trial and error method to effect the proper adjustment. Were it possible to obtain such accurate adjustment, the same would shortly become disorganized upon operation of the screen, which results in shifting and deterioration of the resilient supports. Further, the stress set up in the side frame members are such as to require an extremely heavy structure, and these are naturally accentuated when the screen is out of balance. Therefore, the advantages obtained in this type of screen are overcome by the disadvantages, and leave

much to be desired in the way of a practical, efficient structure.

It is therefore a main object of the present invention to provide a vibratory screen, having all of the advantages heretofore enumerated, without the attending disadvantages, and this is accomplished by the provision of a positive actuated screen having substantially its entire weight supported upon the actuating eccentrics, and provided with substantially non-resisting end-holding means to prevent tipping of the screen on the eccentrics.

Incidental to the foregoing, a more specific object resides in the provision of a vibratory screen having substantially its entire weight supported upon the eccentrics, and provided with substantially non-resisting resilient members connecting the ends of the screen and base to prevent tilting of the screen.

Lastly, a more detailed object in connection with the foregoing resides in utilizing substantially non-resistant, resilient straps connecting the ends of the screen and base, and positioned longitudinally with relation to the path of movement of the screen, each strap being provided with at least one transverse bend.

With the above and other objects in view, which will appear as the description proceeds, the invention resides in the novel construction, combination and arrangement of parts, substantially as hereinafter described, and more particularly defined by the appended claim, it being understood that such changes in the precise embodiment of the herein disclosed invention may be made as come within the scope of the claim.

In the accompanying drawings is illustrated one complete example of the physical embodiment of the present invention constructed according to the best mode so far devised for the practical application of the principles thereof.

In the drawings:—

Figure 1 is an elevation of a screen constructed in accordance with one form of the present invention, parts being broken away and in section to more clearly illustrate the structural features.

Figure 2 is a transverse, fragmentary section taken on the line 2—2 of Figure 1.

Figure 3 is an enlarged fragmentary section taken on the line 3—3 of Figure 1.

Figure 4 is a plan view of the base, illustrating the end-holding straps attached thereto.

Referring now more particularly to the accompanying drawings, wherein like numerals designate like parts, 1 indicates generally a base frame comprising longitudinal side members 2 connected

adjacent their ends by transverse channels 3. When the screen is installed for operation, the base frame 1 is mounted upon any suitable support, at a desired angle, such as illustrated in 5 Figure 1.

Mounted upon the side channels 2, centrally of their ends, are the journal boxes 4, provided with anti-frictional bearings 5, should the same be desired, and having journaled therein the ends of a 10 transverse shaft 6 provided at opposite sides with eccentric portions 7 journaled in anti-frictional bearings 8 carried by the boxes 9.

Mounted upon the boxes 9 is a frame 10, comprising longitudinal side plates 11 having angle 15 irons 11' secured to their outer sides adjacent their lower edges. Attached to the inner faces of the plates 11 are the angles 12, which carry a screening medium 12' clamped to the angles by brackets 13.

Secured on the transverse shaft 7, preferably 20 between the journal boxes 4 and 9, are the overbalanced fly-wheels 13', which may be constructed in any suitable manner, the over-balanced portion being set opposite to the off-set of the eccentric portions 7 of the shaft 6, so as to counter-balance the weight of the screen throughout its movement imparted by the eccentric mounting of the same on the shaft 6. In the present instance, the fly wheel 13' is shown provided with a 25 separate counter-balance weight 14, secured to the web of the wheel between the hub and outer flange by a rivet 15, or any other suitable means. This permits the attachment of weights of various sizes, depending upon the weight of the screen 30 employed.

Secured to one end of the shaft 6 is a pulley 16 driven by a belt 17 connected with a motor 18, mounted on the adjacent side channel 2 of the base frame 1.

The foregoing structure is old in the art. However, the present invention differs therefrom, in that substantially the entire weight of the screen frame 10 is supported upon the shaft 6 through the journal boxes 9 eccentrically mounted thereon, and to prevent tilting or rocking of the main frame 10 about the axis of the eccentrics 7, substantially non-resisting holders 19 are connected to the ends of the side angle irons 11', and the transverse channels 3 of the base frame 1, as best 45 illustrated in Figure 1.

The holders 19 are constructed in the form of spring straps having an intermediate transverse bend 20 providing substantially vertical and horizontal stretches 21 and 22, respectively, of 50 substantially equal length. The upper end of each arm 21 is offset at a right angle for attachment to the under face of one of the angles 11' adjacent its end, while the end of the arm 22 is bent upwardly at a right angle for attachment to the adjacent transverse channel 3.

As previously explained, the entire weight of the screen frame is supported upon the shaft 6, and therefore the spring straps 19 are so designed as to offer substantially no resistance to the circular movement of the screen, and are merely provided as holders to prevent the screen from tilting about the shaft 6. With this in view, the tension of the arms 21 and 22 of the holders 19 is 55 so gauged as to compensate for one another during the vertical circular movement of the screen frame, whereby the resultant resistance to the movement of the screen is reduced to a negligible factor. Incidental to the foregoing, it is further 60 important that the resilient holders be positioned 75

longitudinally with respect to the plane of movement of the screen frame, and while the preferred shape of holder has been illustrated and described in detail, it is to be understood that the same may be modified, and other shapes of holders produced 5 for accomplishing the same results, it being merely necessary that the holders be of such design as to compensate for the circular movement of the screen frame to the extent of offering substantially no resistance to such movement. 10

From the foregoing explanation, considered in connection with the accompanying drawings, it is believed that the operation and advantages of the present structure over previous types of screens will be quite apparent, in that, due to the 15 fact that the vibrating screen is supported substantially entirely upon the shaft 6, it can be readily counter-balanced to the extent that no complicated forces are imposed upon the drive shaft or the frame, and after this is once accomplished, 20 there is no adjustment or resetting required at any time.

Inasmuch as the end holders 19 are designed to offer substantially no resistance to the positive 25 circular movement of the screen imparted by the eccentrics, there is no need to change the counter-balance, as no force would come into play to upset the same. This reduces the cost of the screen, in that expensive counter-balances are not required, and furthermore the proper counter-balance is definitely determined by the simple 30 method of computing the weight of the screen, and the eccentricity to determine the moment of the screen, thus eliminating trial and error methods, and the possibility of subsequently upsetting the adjustment, making the screen fool-proof after it leaves the factory. 35

Since the drive shaft can be counter-balanced with great accuracy, the vibrating screen will not 40 transmit any forces other than the dead load of its own weight to the base frame through the journal boxes 4. Neither will the end holders 19 transmit any forces to the base frame, since they are substantially non-resistant to the action of the screen. 45

Obviously, the foregoing structure requires a 50 minimum amount of power for actuating the screen, since the necessity of compressing and overcoming the force of resilient supports used in other types of screens is eliminated. 55

Another important advantage, especially to the designer, results from the fact that the magnitude and direction of all of the forces exerted on the drive shaft are known, and no undeterminable forces of resilient supports need be considered, 60 thus permitting the accurate determination of stresses at any point on the drive shaft, which eliminates guesswork.

Considering all of the advantages resulting 65 from the present invention over previous types of screens, it will be appreciated that a highly efficient and comparatively inexpensive structure has been provided, which is practically fool-proof, requiring little or no maintenance in the field, other than those necessitated through ordinary 70 wear, and which imparts practically no vibration to the supporting base, which is highly desirable in instances where the screen is installed within a building. Further, the present invention permits of an exceedingly light construction, which not only reduces the cost of manufacture, but also effects a material reduction in the cost 75 of operation.

I claim:—

A vibrating screen comprising a base, a power- 75

driven eccentric shaft journaled on said base, a vibratory screen supported substantially entirely upon said eccentrics and actuated thereby, and independent resilient straps connecting the ends of said screen with the ends of the base, said straps being positioned longitudinally with relation to the plane of movement of said screen, and

having an intermediate transverse bend to provide right angle arms of substantially equal length to render the strap non-resistant to the movement of said screen, the vertical arm being attached to said screen and the horizontal arm being attached to said base.

PETER H. TOEPFER.
